UNITED STATES PATENT OFFICE.

MARTIN J. CARNEY, OF CHICAGO, ILLINOIS.

COMBINED SIGNALING AND TELEPHONE SYSTEM.

1,099,338.

Specification of Letters Patent.

Patented June 9, 1914.

Application filed December 27, 1904. Serial No. 238,420.

To all whom it may concern:

Be it known that I, MARTIN J. CARNEY, a citizen of the United States of America, and resident of Chicago, Cook county, Illinois, have invented a certain new and useful Improvement in Combined Signaling and Telephone Systems, of which the following is a specification.

My invention contemplates a combined 10 signaling and telephone system in which the means for transmitting and receiving fire alarm, police patrol, burglar alarm, night watch, messenger call, and other various similar signals, are totally distinct from 15 and independent of the means for carrying on telephonic communication, and from the signaling transmitting and receiving devices used or required as a part of the telephone apparatus for furnishing telephonic 20 service to the different subscribers of the system.

Generally stated, the object of my invention is to provide a comparatively simple and highly efficient system of the foregoing 25 character; and a special object is to provide such a construction and arrangement as will permit the subscribers' lines to be used for transmitting alarms or other signals at the same time that the circuits are being used 30 for telephonic purposes, without causing any conflict between the two operations; and it is also an object to provide certain 35 details and features of improvement tending to increase the general efficiency and serviceability of a system of this particular character.

To the foregoing and other useful ends my invention consists in matters herein- 40 after set forth and claimed.

In the accompanying drawings Figure 1 45 illustrates a common battery telephone system in which one side of each subscriber's metallic line circuit may also serve as a part of a grounded call-box circuit. Fig. 2 is a similar diagram of a common battery and telephone system, but in this case the call-box circuit includes one side of each of two subscribers' lines and is not grounded as in the preceding figure. Fig. 3 illustrates the 50 call-box circuit arrangement of Fig. 1 applied to a local battery telephone system. Fig. 4 shows the call-box circuit arrangement of Fig. 2 applied to a local battery telephone system.

It will be readily seen that the telephone

circuits and apparatus may be of any suitable known or approved character. The different devices employed in the signaling apparatus may also be of any suitable or desired character. For this reason a detailed 60 illustration of the various devices will be unnecessary.

As illustrated in Fig. 1, my invention comprises a pair of subscribers' line wires 1 and 2 leading from a central station or exchange to the subscriber's station. At the telephone exchange the said subscriber's line, which is of the complete metallic circuit type, terminates in spring-jacks A, B and C and in a battery or central source of current D. The telephone switchboard operator is provided with the usual cord-plug E, adapted for insertion in the said spring-jacks. The subscriber attracts the attention of the telephone switchboard operator by 70 means of a line lamp signal F when a connection with some other subscriber's line is desired. The subscriber signals the operator through the medium of a supervisory lamp signal G when a disconnection is desired. At the subscriber's station the equipment includes the usual battery transmitter H, the receiver I, the hook-switch J, induction coil K, call-bell L, and condenser M. Any suitable arrangement of relays can, of 80 course, be employed for controlling the circuits of the two lamp signals at the exchange or central station. In addition to the apparatus thus employed for giving telephone 85 service, the line wire 2 is connected at the exchange or central station, or at some other place, with a signal receiving apparatus 90 adapted to receive district messenger calls, or other similar signals. As shown, the said signal receiving apparatus, which is totally 95 distinct from and independent of the signal receiving devices for effecting telephone connections, comprises a low frequency alternating current generator N connected with the line wire 2 through the medium of a relay magnet O and impedance coil P and a condenser Q. The said relay magnet has an armature o^1 adapted to control a local circuit including a battery o^2 and the usual recorder or signal-receiving device o^3 . If desired, the said local circuit may also include magnets of one or more relays R for repeating the signals to other offices or stations. It will also be seen that the said generator N is preferably grounded at n . In this way 100 105 110

the said generator is inductively connected with the line wire 2, and suitably connected with the ground. At the subscriber's station, or at some other outlying place or station, the same line wire 2 is connected with ground at 3. In this connection, between the line wire 2 and the ground, one or more call-boxes 4 can be connected in parallel, so that the connection to ground is normally open. With this arrangement, the condenser Q stops the flow of battery current from the battery D, but permits the current to flow out on the line from the generator N when one of the boxes 4 is operated. In other words, the operation of one of the boxes 4 results in the intermittent opening and closing or make and break connection in a grounded circuit, including the ground wire 2 and the generator N. The grounded 20 signalling circuit thus including one side of the subscriber's line circuit, also includes a relay O. Consequently, the signal transmitted by the call-box 4 is repeated or transmitted by the relay O to the local circuit including the recorder, or other appropriate signal receiving device o². At the same time that a district messenger or other similar signal is being transmitted over a circuit, including one side of a subscriber's line, 30 the telephone apparatus or equipment at the subscriber's station may be employed for either signaling or communicating with the operator at the central station or exchange or with some other subscriber. Thus in a system such as shown in Fig. 1 two distinct kinds of service may be given, neither one conflicting with the other. This is for the reason that although one side of each subscriber's line may be common to both kinds 40 of service, the transmitting and receiving device for one kind of service are totally distinct and independent from the transmitting and receiving devices employed in giving the other kind of service. In other words, the operator who receives the calls for telephone connections has nothing whatever to do with the signal receiving devices by which a district messenger call or other similar signal, is transmitted over the same 50 line. So, also, the subscriber's telephone equipment connected with a line may be in use at the same time that some one is using a call-box connected with the same line. And thus the two services, to-wit, the telephonic service and the call-box fire alarm, police patrol, or other similar service, are operatively distinct and independent of each other, although structurally the two kinds of service are each dependent upon the same 60 subscriber's line wires. The ground connection from the battery D may be provided with an impedance coil S so as to prevent the passage of either voice or generator currents. It will be understood that the impedance coil P also serves to prevent the

passage of voice currents, although not of a character to prevent the passage of the necessary generator currents.

In Fig. 2 the telephone apparatus is the same as in Fig. 1, and this is practically true of the call-box apparatus. In Fig. 2, however, it will be seen that the generator N¹ is bridged across from the subscriber's line wire a² to the subscriber's line wire a² of another line. In this bridge, at each side of said generator are the condensers Q¹—Q¹ and the impedance coils P¹—P¹. Said bridge also includes the magnet of a relay O¹. In Fig. 2 the signal receiving apparatus is the same as that shown in Fig. 1. At the subscriber's station or at the other outlying places or stations, the call-boxes 4^a are also bridged from one line a² to the other line wire a². Consequently, in Fig. 2 the telephone circuits are not only entirely metallic, but the circuits for the call-boxes are also entirely metallic. Each call-box circuit includes one side of each of two subscribers' lines. Obviously, however, and as in the previous case, the apparatus for receiving the call-box signals is totally distinct from the apparatus for receiving the telephonic signals. The means for transmitting the signals by which the subscriber gets a telephone connection are also totally distinct from the call-boxes or transmitting devices by which the district messenger, police patrol or firm alarm signals are transmitted. For this reason, as in the previous case, the apparatus for giving telephone service is totally distinct from and in no way conflicts with the apparatus for giving the district messenger, fire alarm, police patrol, or other like service.

In Fig. 3 the call-box apparatus—that is to say, the apparatus by which the district messenger, fire alarm or police signals are transmitted and received, is the same as that shown in Fig. 1. In Fig. 3, however, the said call-box transmitting and receiving apparatus is applied to all telephone systems employing local batteries T at the subscriber's station, rather than the previously described central source of current. But the call-box circuit in Fig. 3 is the same as in Fig. 1, as it is simply a grounded circuit including only one side of the subscriber's line. In Fig. 3, the subscriber uses a generator U for operating the calling and clearing out drops or relays V and W at the central station. The operation of a telephone system of this character will be readily understood.

In Fig. 4 the call-boxes and devices for receiving the signals transmitted by the call-boxes are connected with the line wires in a manner similar to that shown in Fig. 2. In Fig. 4, however, the telephonic apparatus or system is of the character shown in Fig. 3. In other words, in Fig. 4, the local bat-

series T^1 are employed at the subscribers' stations, and the signals for telephonic connections and disconnections are effected through the medium of a generator U^1 at the subscriber's station, and the drops or relays V^1 and W^1 at the central station.

It is evident, therefore, that a system embodying the principles of my invention may be constructed in various ways. In any case, however, it will be seen that no single subscriber's line is included in both sides of a call-box circuit, but the arrangement being preferably of such character that each subscriber's line—that is to say, each subscriber's line employed for such purpose—serves merely as one side of a call-box circuit. Furthermore, it will be seen that the arrangement is preferably such that only one side of each metallic telephone subscriber's line circuit is appropriated for use as one side of a call-box circuit. In other words, even though the call-box circuit is entirely metallic, it is preferable to obtain a circuit of this character by employing only one side of each of two metallic subscribers' line circuits. It is obvious, however, that both sides of each subscriber's metallic line circuit may be employed for call-box service and that this may be done in any suitable or desired manner.

From the foregoing it is obvious that I employ the ordinary telephone subscribers' line wires, or that I employ any other suitable line wires for giving different kinds of service, each service being totally distinct from and independent of the other, so far as operations are concerned, but the different kinds of service, and the system as a whole, being dependent upon the same subscribers' line wires. Of course, the telephone system may be installed first, and the call-box police patrol, fire alarm or other like apparatus then applied to the telephone subscriber's line circuit in the manner described. So, on the other hand, the call-boxes or district messenger system may be first installed, and the line wires then made to do double duty by installing the telephone switchboard apparatus and the subscriber's telephone equipment in such manner as to utilize the line wires already in use in giving service from the call-boxes or other like devices. Preferably, however, the call-box, and the signal receiving apparatus therefor, are installed and employed in connection with a telephone system which has been previously installed and put in operation.

In Figs. 3 and 4 it is obvious that no condensers need be employed in the recording or signal receiving apparatus connected with the subscribers' lines to receive signals from the call boxes. This, of course, is for the reason that no battery current is employed on the lines for charging the transmitters at the subscribers' stations. In Fig. 3, there-

fore, the impedance coil P^2 can be connected directly with the line, rather than through the condenser as shown in Fig. 1. Also, in Fig. 4 the two impedance coils P^3 can be connected directly with the subscribers' lines, rather than through the condensers shown in Fig. 2.

What I claim as my invention is:

1. The combination of a subscriber's telephone line, suitable signaling devices, a source of current for both talking and signaling purposes, and a signal circuit including signal transmitting and receiving devices and a central source of current which are distinct from the means employed in furnishing telephone service, the said subscriber's line including only a part of the said signaling circuit, the signal receiving devices being located at a central station.

2. The combination of a metallic line circuit, a central battery for charging said line circuit when the latter is closed, telephone apparatus suitably connected with said metallic line circuit, a signaling circuit including a call-box, and a relay and an alternating current generator in said signaling circuit, said call-box and relay being distinct from the means employed for furnishing telephone service, and the said signaling circuit also including impedance and capacity interposed between the said relay and the said metallic line circuit.

3. The combination of a telephone subscriber's line, and a signaling circuit including a call-box and an alternating current generator and a relay, said call-box and relay and generator being distinct from the means employed for furnishing telephone service, and the said telephone subscriber's line including a part of said signaling circuit.

4. The combination of a complete telephone exchange system, a signaling system, a separate central source of operating current for each system, the signal transmitting and receiving devices of the signaling system being distinct from the means employed for furnishing telephone service, but one or more of the telephone circuits including part of one or more of the signaling circuits of the said signaling system, whereby the transmitting and receiving apparatus of the two systems, although distinct from and independent of each other, utilize simultaneously the subscriber's line wires which are common to both systems, each system having a distinct or separate central station.

5. A system comprising two distinct electrical transmission systems each having a central source of current, adapted to operate simultaneously, whereof the entire transmitting and receiving apparatus and central source of current of each system is distinct from and independent of the transmitting and receiving apparatus and source of cur-

rent of the other system, but wherein one or more of the line circuits of one system includes part of one or more of the line circuits of the other system, each system having its own central station, substantially as described.

6. A combined telephone and alarm system comprising telephone lines, a central source of current for use in giving telephone service over said lines, and a separate source of current common to said lines and adapted

for use only in transmitting alarm signals over said lines, said telephone service and alarm signals adapted to be operated simultaneously.

15

Signed by me at Chicago, Cook county, Illinois, this 18th day of November, 1904.
